UNITED STATES PATENT OFFICE.

GEORGE SCHNITZLER, OF NEW YORK, N. Y., ASSIGNOR TO FRIEDBERGER-AARON MANUFACTURING COMPANY, OF PHILADELPHIA, PENNSYLVANIA, A CORPORATION OF PENNSYLVANIA.

DESIGN FOR A RIBBON.

52,680.

Specification for Design.

Patented Nov. 12, 1918.

Application filed April 19, 1917. Serial No. 163,299. Term of patent 3½ years.

To all whom it may concern:

Be it known that I, GEORGE SCHNITZLER, a citizen of the United States, residing in the city of New York, county of New York, and State of New York, have invented a new, original, and ornamental Design for a Ribbon, of which the following is a specification, reference being had to the accompanying drawings, which form a part thereof.

The ribbon comprises a longitudinally extending central strip *a* and longitudinally extending side strips *b*, the side strips in appearance distinctively contrasting with the central strip. Interlaced with the fabric of the said strip are threads *c* forming the

shape of the parts of a buckle, said threads being distinctive in appearance and contrasting especially with the central strip.

The figure is a plan view of a part of a ribbon embodying my design.

I claim—

The ornamental design for a ribbon, as shown and described.

In testimony of which invention, I have hereunto set my hand, at New York, on this 16th day of April, A. D. 1917.

GEORGE SCHNITZLER.
